UNITED STATES PATENT OFFICE.

AUGUST CHWALA, OF VIENNA, AUSTRIA, ASSIGNOR TO ODERBERGER CHEMISCHE WERKE AKTIENGESELLSCHAFT, OF ODERBERG, CZECHOSLOVAKIA, A JOINT STOCK COMPANY OF CZECHOSLOVAKIA.

PROCESS FOR MANUFACTURING COLLOIDAL COMPOUNDS OF ARSENIC.

No Drawing.

Application filed August 20, 1924. Serial No. 733,222.

To all whom it may concern:

Be it known that I, AUGUST CHWALA, a citizen of the Republic of Austria, residing at Vienna, Austria, have invented certain new and useful Improvements in a Process for Manufacturing Colloidal Compounds of Arsenic, of which the following is a specification.

The present invention relates to the manufacture of colloidal compounds of arsenic and particularly of derivatives of arsenic acid and of arsenious acid. These compounds may be used in the form of a sol or of a gel preferably for destroying animal parasites of plants.

There exist known methods for bringing arsenate of lead obtained by mutual reaction of salts of arsenic acid and of lead-salts in the presence of protective colloids into a finely divided state, which methods consist in repeatedly treating the arsenate of lead formed in this manner in some liquid medium, to which a protective colloid is added. This finely divided state, has been designated as "semi-colloidal." Trials aiming at the production of true colloids by this method were not successful.

As to arsenate of lead, obtained directly from the oxides of lead and other compounds of arsenic by the usual methods known at present, such as for instance arsenate of lime, there was prior to the present invention no possibility of reducing them to a state of such fine dispersion as is necessary for obtaining homogenous solutions appropriate for application on plants by sprinkling.

Furthermore trials have been made which consisted in first reducing the reacting components by some dispersion method to a colloidal form, thereafter initiating the oxidation by means of chlorine and then continuing the oxidizing process by means of the oxygen contained in the lead oxide. However, satisfying results could not be obtained by this method.

As a result of very exhaustive experiments I have found that the reduction of arsenic compounds to a colloidal state by mere disintegration is not possible, not even in the presence of considerable quantities of protective colloids.

The present invention consists of a method for producing colloidal compounds of

arsenic by mechanical dispersion in the presence of protective colloids, in which method the dispersion is carried out in the presence of free ions of metallic acids, that is to say in the presence of salts derived from higher oxides of a metal combining with oxygen in several proportions, the said oxides having the property of forming acids. As far as the principle is concerned, it is of no importance whether the free ions of metallic acids are added to the liquid medium in the form of dissociated solutions or if compounds generating the said free ions are formed in the solution itself by chemical reaction.

For transforming e. g. arsenate of lead, into the colloidal state the dispersion is initiated by the presence of small quantities of plumbate-ions, for instance by the presence of alkaline plumbates or particularly plumbates of earth alkalies, but care is to be taken during this step to have also free ions of lead in the reacting mass, although in small concentration, which result is reached by adjusting the concentration of the reacting mass to a certain degree.

Furthermore I have found that the transformation into the colloidal state is favourably influenced by the addition of high molecular weight compounds having the tendency of forming complex compounds or adsorption-compounds, no matter if these additions are of organic or inorganic nature.

The following compounds have been found to be particularly effective when used as additions for promoting the transformation of arsenic compounds into the colloidal state, by means of metallic acid ions, viz: inorganic compounds of silicon, arsenic and antimony, stannate of potassium, salts of molybdic acid, salts of several aliphatic or aromatic acids, such as for instance succinate of sodium, malonate of zinc and meta-stannic acid.

Also sulphides and thionates produce a similar effect, but they have the draw-back, that the final product contains small quantities of lead sulphide, the generation of which is due to the dissociated lead-ions, and owing to which the arsenate of lead finally assumes a dark colour and an unsightly aspect.

The dispersing qualities of the metallic

acid ions and the tendency of forming adsorption compounds of the above named substances will not come out to its full extent except under the condition, that these additions are effected successively and in certain cases alternately. Thus by one operation colloidal pastes containing about 57% of colloidal arsenate of lead or even more may be obtained without the colloidal solubility or the reversibility of the gel being deteriorated by the increase of concentration.

Example.

15 3000 parts by weight of a paste of lead-arsenate obtained by the known method and containing about 50% of water are dispersed in one of the known mechanical devices with 50 parts by weight of calcium 20 plumbate suspended in 100 parts of water, and with 800 parts by weight of a 20% solution of the sodium salt of protalbinic acid, or, instead of the latter, with waste sulfite liquor. Then the second reagent is added, 25 consisting of 50 parts by weight of an aqueous suspension of calcium plumbate, the addition being effected very slowly and gradually at intervals. After intimate mixing by agitating and stirring the third reagent is added, viz, 10 parts by weight of sodium antimoniate, intense mixing and stirring being continued until a small test quantity of the mass, when poured into water, forms a perfectly homogenous and durable milk.

The product thus obtained is a uniform colloid. It does not deposit a sediment in the flocculometer with two branches of Wolfgang Ostwald and Hahn (Kolloid-Zeitschrift 30, 62, 1922), it is readily coagulated by anyone of the electrolytes, does not penetrate through an animal membrane by diffusion and shows in the ultra-microscope the characteristic movement called the Brownian movement. It therefore proves to be in fact a perfect true colloid.

This product also shows the appreciable property of constituting a reversible gel. Total dehydration will destroy the colloidal state. But if the product is dried at low temperatures, say under 40° centigrade to such degree, that it still contains a small amount of water, it remains after the drying colloidally soluble in water.

55 In the same manner Schweinfurt-green having the formula

may be transformed into a colloid with a high molecular weight copper compound, as for instance by addition of the so-called Fehling's solution.

The colloidal arsenic compounds thus manufactured are homogenous preparations readily and perfectly wetting the plants and

are used for destroying the animal parasites on them. By practical experience it has been found, that the colloidal arsenate of lead adheres particularly well to the plant, that it perfectly wets its leaves and all other parts and that the product can be employed most economically. Even solutions containing not more than 0.25% are of a striking insecticidal effect.

In the foregoing specification as well as in the following claims by the term "salts" not only the compounds of an equivalent of an acid with an equivalent of a base joined by the ordinary (principal or normal) valencies are understood, but also all other compounds, particularly those of complex nature, which are not combined in the ratio of the principal or normal valencies, but are connected to larger molecules by residual affinity or by additional (auxiliary) valencies. The term "compounds of complex nature" has been used to include not only the compounds in the strict sense of this word but also the so-called adsorption compounds.

What I claim is:

1. In the art of producing colloidal compounds of arsenic the step which consists in mechanically dispersing the arsenic compound in presence of protective colloids and of salts of metallic acids derived from higher oxides of a metal combining with oxygen in several proportions, the said oxides having the property of forming acids.

2. In the art of producing colloidal compounds the step which consists in mechanically dispersing the arsenic compound in presence of protective colloids and of salts of a metallic acid.

3. In the art of producing colloidal compounds the step which consists in mechanically dispersing the arsenic compound in presence of protective colloids and of salts of plumbic acid.

4. In the art of producing colloidal compounds the step which consists in mechanically dispersing the arsenic compound in presence of protective colloids and of salts of plumbic acid with addition of compounds of high molecular weight having the property of forming compounds of complex nature with insoluble arsenic compounds.

5. In the art of producing colloidal compounds the step which consists in mechanically dispersing the arsenic compound in presence of protective colloids and of salts of alkaline earths and of plumbic acid with addition of compounds of high molecular weight having the property of forming compounds of complex nature with insoluble arsenic compounds.

6. In the art of producing colloidal compounds the step which consists in mechanically dispersing the arsenic compound in presence of protective colloids and of cal-

cium plumbate with addition of compounds of high molecular weight having the property of forming compounds of complex nature with insoluble arsenic compounds.

5 7. In the art of producing colloidal compounds the step which consists in mechanically dispersing the arsenic compound in presence of protective colloids and of salts of plumbic acid with addition of compounds 10 of high molecular weight having the property of forming compounds of complex nature with insoluble arsenic compounds the additions being effected successively.

8. In the art of producing colloidal compounds the step which consists in mechanically dispersing the arsenic compound in presence of protective colloids and of salts of plumbic acid with addition of compounds of high molecular weight having 15 the property of forming compounds of complex nature with insoluble arsenic compounds the additions being effected successively and alternately.

9. In the art of producing colloidal compounds the step which consists of mechanically dispersing the arsenic compounds in presence of protective colloids and of calcium plumbate with additions of protalbinic acid.

10. In the art of producing colloidal compounds the step which consists in mechanically dispersing the arsenic compounds in presence of protective colloids and of calcium plumbate with additions of protalbinic acid and of antimoniate of sodium.

11. Preparations for the protection of

plants (for destroying the animal parasites of plants) consisting of a colloidal compound of arsenic, protective colloids and of salts of metallic acids derived from higher oxides 40 of a metal combining with oxygen in several proportions, the said oxides having the property of forming acids.

12. Preparation for protecting plants consisting of a colloidal arsenic compound, of 45 protective colloids and of salts of metallic acids.

13. Preparations for protecting plants consisting of a colloidal arsenic compound, of protective colloids, salts of plumbic acid 50 and compounds of high molecular weight having the property of forming compounds of complex nature with insoluble arsenic compounds.

14. Preparation for protecting plants consisting of a colloidal arsenic compound, protective colloids, plumbate of calcium and compounds of high molecular weight having 55 the property of forming compounds of complex nature with insoluble arsenic compounds.

15. Preparation for protecting plants consisting of a colloidal arsenic compound, protective colloids, calcium plumbate and protalbinic acid.

16. Preparation for protecting plants consisting of a colloidal arsenic compound, protective colloids, calcium plumbate, protalbinic acid and antimoniate of sodium.

In testimony whereof I have affixed my 70 signature.

AUGUST CHWALA.
